UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DUMP-DOOR-OPERATING MECHANISM.

1,085,244.

Specification of Letters Patent.

Patented Jan. 27, 1914.

Application filed February 10, 1913. Serial No. 747,236.

To all whom it may concern:

Be it known that I, ARGYLE CAMPBELL, a citizen of the United States, residing at Chicago, in the county of Cook and State of Illinois, have invented a certain new and useful Improvement in Dump-Door-Operating Mechanism, of which the following is a full, clear, concise, and exact description, reference being had to the accompanying drawings, forming a part of this specification.

My invention relates to improvements in dump door operating mechanism.

More particularly it relates to dump door operating mechanism for the kind of dump cars having a series of doors extending from end to end of the car body or doors between the body bolster and the end of the car.

Among the objects which my invention attains is that of removing a source of inconvenience and danger to trainmen in the practical operation of railroads, and in the coupling and uncoupling of cars, by obviating the necessity of projecting the ends of the longitudinally disposed operating shaft employed in cars of the kind referred to beyond the plane of the car ends. The manner of accomplishing this and other objects of my invention will appear more clearly from the description herein following taken in connection with the accompanying drawings, in which—

Figure 1 is an elevation of the side portion of a railroad car, together with the door operating mechanism. Fig. 2 is an elevation of the end portion of a car showing the end of the operating shaft.

In the drawings 3 represents the body of a dump car of any suitable construction, 4 the wheels, 5 the side sills, 6 the upright stakes or frame members of the body, 7 the upright sides of the car body, 8 an end sill, 9 an end of the car body, 10 a railroad track rail, 11 the center sills. The upright sides 7 are turned inwardly at the bottom, as illustrated at the point indicated by the numeral 12. The operating shaft 13 extends along the side of the car body, and operates in suitable journals provided therefor. The doors 14, 14 are each operatively connected to the said shaft by the door opening devices 15, 15, which may be of any suitable kind.

Secured, preferably by rivets, to the upright portion of the car side near the end of

the car body are the angle irons 16 and 17. 55 These irons depend from the car body, and are spaced apart, 17 being the forward and 16 the rear iron. A block or plate 18 is preferably placed between one of said irons, preferably the forward iron 17, and the inwardly 60 turned portion of the car side, the said block or plate 18 being preferably provided with an outer flange 19 through which it is riveted to the iron 17, and an inner flange 20 through which it is riveted to the car body. The 65 block or plate 18 is perforated longitudinally of the car, and furnishes a bearing for the operating shaft which passes therethrough. Said shaft terminates back of the plane of the car's end 9 and in front 70 of the iron 17, which with the block or plate 18 are sufficiently removed from the end of the car to permit the latch wheel 21, the pawl 22, the lock 23, and the ratchet lever 24 containing ratchet wheel 25 and 75 ratchet pawl 26, all to be placed on the operating shaft's end back of the plane of the car's end. The pawl 22 for the latch wheel is secured to the plate 18, and the lock 23 for said pawl is preferably secured to the 80 iron 17. The iron 17 is secured at its lower end to the car body by the brace 27, and the iron 16 by the brace 28.

It will be apparent that by the construction described a secure end bearing for the 85 operating shaft is provided, although various parts could be slightly altered or changed about without affecting the important feature of providing novel and practicable means for shortening the operating shaft to the length of the car body or less, and thereby not endanger or inconvenience those who in the operation of trains are obliged to work thereabout.

I claim:—

1. In a dump car, a car body, doors from end to end in said car body, a longitudinally disposed operating shaft journaled thereon, said shaft being of a length not greater than the length of the car body, a bar secured to 100 the car body, a plate secured between said bar and the car body, and adapted to receive the operating shaft therethrough, said plate being back of the plane of the end of the car body.

2. In a dump car, a car body, body bolsters therein, a series of doors extending beyond the body bolsters at either end, an oper-

95

105

ating shaft of no greater length than the length of the car body, door opening devices connecting the doors and shaft, journals for said shaft, one of said journals comprising a 5 perforated plate and a bar, the said bar being secured to the car side, and the plate being secured between the said bar and car side, back of the car end.

3. In a dump car having doors between 10 the body bolsters and the car ends, upright sides having a bottom inwardly turned portion, doors, an operating shaft journaled to the outside of the car, and along the inwardly turned portion of the side of the car, door opening devices connecting the shaft with the doors, a bar dependent from the upright portion of the side of the car, a plate secured between said bar and the car side, and adapted to receive the operating shaft therethrough, the said shaft's ends being 20 back of the car end.

4. In a dump car having doors between the body bolsters and the car ends, upright sides having a bottom inwardly turned portion, doors, an operating shaft journaled to the outside of the car, and along the inwardly turned portion of the side of the car, said shaft being of a length not greater than the length of the car body, door opening 25 devices connecting the shaft with the doors, a bar dependent from the upright portion of the side of the car, a plate secured between said bar and the car side, and adapted to receive the operating shaft therethrough, the said plate being provided 30 with flanges through which it is secured between said bar and the car side.

5. In a dump car having doors between the body bolsters and the car ends, upright 40 sides having a bottom inwardly turned portion, doors, an operating shaft journaled to the outside of the car and along the inwardly turned portion of the side of the car, said shaft being of no greater length than the length of the car body, door opening devices 45 connecting the shaft with the doors, a bar dependent from the upright portion of the side of the car, a plate secured between said bar and the car side, and adapted to receive the operating shaft therethrough, and braces secured at one end to the said bar and to the car side at the other end.

6. In a dump car having doors between the body bolsters and the car ends, upright 55 sides having a bottom inwardly turned portion, doors, an operating shaft journaled to the outside of the car and along the inwardly turned portion of the side of the car, door opening devices connecting the shaft with the doors, a bar dependent from the upright portion of the side of the car, a plate secured between said bar and the car side, and adapted to receive the operating shaft therethrough, a further bar dependent 60 from the upright portion of the car side,

and ladder rungs secured between said bar and the first mentioned bar.

7. In a dump car, a car body, doors from end to end in said car body, a longitudinally disposed operating shaft, means for mounting said shaft, the said shaft being of a length not greater than the length of the car body. 70

8. In a dump car, a car body, doors therein, certain of said doors being between the body bolster and the end of the car, an operating shaft, door opening devices connecting the doors and operating shaft, the ends of said operating shaft terminating between the planes of the car ends. 75

9. In a dump car, a car body, doors from end to end in said car body, a longitudinally disposed operating shaft for said doors, said shaft being of a length not greater than the length of the car body, brackets for said shaft, the end brackets being each mounted between the end of the car and the inner end of the end door. 80

10. In a dump car, a car body, doors from end to end of the said body, a longitudinally disposed operating shaft of a length not greater than the length of the car body for said doors, brackets for said shaft, the end brackets being each mounted back of the end of the car and farther distant therefrom than the nearest edge of the end door of the car. 90

11. In a dump car, a car body, doors from end to end in said car body, a longitudinally disposed operating shaft for said doors, means for mounting said shaft, said means including an end bracket for said shaft and a car ladder, said bracket being secured to said ladder. 100

12. In a dump car, a car body, doors from end to end in said car body, a longitudinally disposed operating shaft for said doors, means for mounting said shaft, said means including an end bracket for said shaft and a car ladder, said bracket being secured to said ladder and between the ladder and car body. 110

13. In a dump car, a car body, doors from end to end in said car body, a longitudinally disposed operating shaft for said doors, means for mounting said shaft, said means including an end bracket for said shaft and a car ladder, said bracket comprising a flat plate secured between said ladder and the car body. 115

14. In a dump car, a car body, doors from end to end in said car body, a longitudinally disposed operating shaft for said doors, means for mounting said shaft, said means including an end bracket for said shaft and a car ladder, said bracket comprising a flat plate secured between said ladder and the car body, and having riveting flanges adjacent the car body. 125

15. In a dump car, a car body, body bol-

180

sters, doors from end to end in said car body, a longitudinally disposed operating shaft for said doors, said shaft being of no greater length than the length of the car body, 5 brackets for the mounting of said shaft and a ladder, the end brackets being secured between said ladder and the car, and being dis-

posed between a body bolster and the adjacent car end.
